CLAIM

The ornamental design for a transparent walker tray, as shown and described.

DESCRIPTION

FIG. 1 is a first top perspective view of the transparent walker tray;

FIG. 2 is a second top perspective view of the transparent walker tray;

FIG. 3 is a top plan view of the transparent walker tray;

FIG. 4 is a bottom plan view of the transparent walker tray;

FIG. 5 is a rear edge view of the transparent walker tray;

FIG. 6 is a front edge view of the transparent walker tray;

FIG. 7 is a first side edge view of the transparent walker tray;

FIG. 8 is a second side edge view of the transparent walker tray; and,

FIG. 9 is a third top perspective view of the transparent walker tray shown in a condition of use.

The broken lines in FIG. 9 illustrating a walker apparatus, a user, and a ball form no part of the claimed design.

1 Claim, 4 Drawing Sheets
